INVENTOR.

Oscar Wm Trisch.

UNITED STATES PATENT OFFICE.

OSCAR WM. TRILSCH, OF WHITESTONE, NEW YORK, ASSIGNOR TO OSCAR TRILSCH CO.,
OF WHITESTONE, NEW YORK.

METHOD OF COVERING PAPER OR WOODEN BOXES.

1,386,384.

Specification of Letters Patent.

Patented Aug. 2, 1921.

Application filed May 23, 1921. Serial No. 471,815.

To all whom it may concern:

Be it known that I, OSCAR WM. TRILSCH, citizen of the United States, and resident of Whitestone, in the county of Queens and State of New York, have invented certain new and useful Improvements in Methods of Covering Paper or Wooden Boxes, of which the following is a specification.

This invention relates to an improved method of covering paper or wooden boxes, and has for its object the provision of a simple and inexpensive method of applying and affixing to the outside of paper or wooden boxes, a covering of velvet, satin, or other similar material.

Referring to the drawings:

Figure 1 shows a blank "A" such as usually used to make the paper boxes. This blank is usually scored on the lines "a" and bent up on these lines into a box shape.

Fig. 2, shows a sample blank "B" of the covering material which may be velvet, satin, felt, or even leatherette, paper or other similar materials.

Fig. 3 shows one of these blanks bent up and entirely covered or wrapped with a paper covering turned over the top edges of the box inwardly and down against the inner walls thereof. This method may be used when a cheap grade of velvet is used and in such cases the paper covering of the box would be made the same color as the velvet in order to sustain its color tone and to reinforce the box.

Fig. 4 shows another method of bending up and holding the blank in shape of a box by what is called corner staying which consists in applying a piece of tough paper "b" coated with adhesive to each corner as shown.

Fig. 5 shows still another method in which the blank is bent up and then a strip of tough paper "c" wound completely around the sides and lapped as at "d".

Fig. 6 shows the box with the covering material folded up against the sides.

Fig. 7 shows the excess covering material being clipped off one corner by means of a shears.

Fig. 8 shows the upstanding edges of covering material above one corner being clipped off by means of a shears.

Fig. 9 shows the box covered on the outside with the upstanding edges ready to

turn inwardly and downwardly into and 55 against the inside of the box.

Fig. 10 shows a completely covered and finished box.

No claim is made for invention of any of these style boxes they are just merely illustrated to show some of the kinds of boxes 60 that may be covered by my method.

In practice this blank of covering material is coated with adhesive on one side and a box as described centered upon the blank 65 on the side coated with adhesive. The edges of the coated velvet blank which extend beyond the bottom of the box are then folded up against the sides of the box as at "e" pressed firmly thereto to cause them to ad- 70 here, when this has been done the box will appear as in Fig. 6.

The next step in the method is shown in Fig. 7 and consists in cutting off with a shears the excess covering material "f" 75 at each corner. The action of the shears when making this cut is to press the coated sides of the covering material firmly together and make a perfectly straight corner.

After this is done the upstanding edges of 80 the covering material which extend above the sides of the box can be turned inwardly and down into the box against the inner walls, completing the covering of the box. However, in order to provide for the thick- 85 ness of the box itself a better result is produced by clipping off the corners "g" of the upstanding edges of the covering material which extend above the corners of the box as shown in Fig. 8. When this has been 90 done the box with its bottom and sides covered and with its upstanding edges "h" of covering material, with the corners clipped will appear as shown in Fig. 9.

The next operation is to turn these edges 95 of covering material with the clipped corners inwardly and down against the inner walls of the box to make a completely covered and finished box as shown in Fig. 10. Clipping the corners as described makes it 100 possible to make a neat inner corner in the box.

Heretofore velvet covered boxes have always been made by covering the sides with a strip of covering material extending 105 completely around the box and either butt-jointed or lapped. The strip being made wider than the height of the side of the box,

the portion of the strip extending above the top edges of the box being folded inwardly and down against the inner walls of the box and the portion of the strip extending below 5 the bottom of the box being turned over the bottom edge and against the bottom of the box. This leaves the bottom unfinished and requires that an extra bottom piece, usually termed a button, which consists of a piece of 10 cardboard or similar material covered with velvet with the edges turned over the back be used to cover up this unfinished bottom by affixing it thereto with adhesive. It will therefore be seen that my method of covering 15 a box entirely eliminates the use of this so called button which saves the labor involved in making this part. Besides the edges of the box do not make as good an appearance as when the velvet is turned directly over the 20 edge from the bottom to the sides in one piece. It has another distinct advantage in that it saves about twenty-five per cent. of the covering material required to cover the box.

25 My improved method of covering boxes as described therefore makes possible a saving of at least twenty-five per cent. of the covering material and at least one-third of the labor required by any methods heretofore used.

30 What I claim is:—

1. The method herein described of covering boxes, starting with a rectangular blank of covering material, coated with adhesive, 35 centering the box upon said blank, folding covering blank up against the sides of said box, shearing off at each corner the surplus

covering material and turning the upstanding edges inwardly and down into and against the inner surface of the sides of said 40 box.

2. The method herein described of covering boxes, starting with a rectangular blank of covering material, coated with adhesive, centering the box upon said blank, folding 45 the remainder of said blank up against the sides of said box with sufficient pressure to cause sides of said blank to adhere to said box, shearing off the surplus covering material at each corner, and further, clipping 50 the upstanding edges above each corner of said box so that the upstanding edge of said blank is in each case shorter than the adjacent side of the box, then folding the said upstanding edges inwardly and down 55 against the inside of the box.

3. The method herein described of covering boxes starting with a piece of covering material coated with adhesive, placing the box upon said piece, folding the covering material projecting around the box, up against the sides of said box with sufficient pressure to cause said covering material to adhere to said box, shearing off the surplus covering material at each corner, and further, clipping 60 the upstanding edges above each corner of said box so that the upstanding edge of said piece is in each case shorter than the adjacent side of the box, then folding the upstanding edges inwardly and down against 65 the inside of the box.

Signed at Whitestone in the county of Queens and State of New York.

OSCAR WM. TRILSCH.
